UNITED STATES PATENT OFFICE.

ARTHUR WESLEY TEASLEY AND MILLARD VAN, OF OZONE, TENNESSEE.

TOBACCO-CUTTER.

No. 881,357.

Specification of Letters Patent. Patented March 10, 1908.

Application filed March 12, 1907. Serial No. 362,067.

To all whom it may concern:

Be it known that we, ARTHUR WESLEY TEASLEY and MILLARD VAN, citizens of the United States, residing at Ozone, in the county 5 of Cumberland and State of Tennessee, have invented new and useful Improvements in Tobacco-Cutters, of which the following is a specification.

This invention relates to a cutting device 10 intended for use in cutting plug tobacco.

The invention has for one of its objects to improve and simplify the construction and operation of devices of this character so as to be comparatively inexpensive and easy to 15 construct, composed of few parts, and efficient and reliable in use.

A further object of the invention is the provision of a tobacco cutting device which is equipped with a treadle-actuated means 20 for operating the knife or cutter, said means including an adjusting device, whereby the apparatus can be adapted to counters of different heights.

With these objects in view and others as 25 will appear as the description proceeds, the invention comprises the various novel features of construction and arrangement of parts 30 as will be more fully described hereinafter and set forth with particularity in the claims appended hereto.

In the accompanying drawing, which illustrates one of the embodiments of the invention, the figure is a perspective view of the rear of a counter with the cutting device applied thereto.

Referring to the drawing, 1 designates a store counter on which the apparatus is mounted. The apparatus comprises a base-plate 2 that is set into the counter top and 40 secured thereto by screws 3, and rigidly secured to the plate is an inverted U-shaped frame 4 having longitudinal slots 5 in the vertical portions thereof for receiving the blade or cutter 6. This blade is adapted to 45 have a combined vertical and horizontal movement so as to sever the plug of tobacco designated by 7 with a sliding cut. One end of the blade is connected by the link 8 with an operating lever 9 fulcrumed at its front 50 end on the rear corner of the frame 4, and the forward portion of the blade is suspended from the frame 4 by a link 10 that is inclined rearwardly of a plane passing through its top end so as to assist in imparting to the knife a

sliding or drawing movement. The outer 55 end of the lever 9 is connected by a pitman 11 with a foot lever or treadle 12 that is fulcrumed on a post 13 mounted on the floor. The pitman 10 includes a turnbuckle 14, whereby the distance between the foot lever and knife 60 lever 9 can be varied to adapt the apparatus to counters of different heights. The front end of the treadle 12 projects beyond the floor post 13 and has an adjustable counterbalance weight 15 that serves to restore the treadle 65 and, through the intervening mechanism, the knife to their normal position. In other words, the weight serves to hold the knife or blade in raised position so that a plug of tobacco can be inserted thereunder and sev- 70 ered merely by depressing the foot lever 12.

From the foregoing description taken in connection with the accompanying drawing, the advantages of the construction and of the method of operation will be readily apparent, and while we have described the principle of operation of the invention, together with the device which we now consider to be the best embodiment thereof, we desire to have it understood that the device 75 shown is merely illustrative and that such changes may be made when desired as are within the scope of the claims.

Having thus described the invention, what we claim is:—

1. A tobacco cutter comprising a base plate, an inverted U-shaped frame thereon, a blade guided on the vertical portions of the frame, a link hingedly connected at one end to the blade at a point intermediate its ends 90 and at the opposite end to the frame adjacent one corner thereof; a lever fulcrumed at one end on the frame at the other corner thereof and extending outwardly from the frame, and an inclined link connected at one 95 end with the lever at a point intermediate the ends of the lever, and at the opposite end with the extremity of the blade and the lever acting directly through the second link for depressing and raising the blade and the 100 first link serving to impart a drawing movement to the blade.

2. In a device of the class described, the combination of a plate, an inverted U-shaped frame rigid thereon, a blade guided on the 105 frame, an inclined link pivoted on the frame and connected with the blade to suspend the latter, a lever fulcrumed at one

end on the frame, a link inclined toward the other and connected at one end of the blade and with the lever at a point intermediate its ends, a treadle, means for supporting the 5 same, and a pitman between the treadle and outer end of the lever, said pitman including adjustable sections for lengthening or shortening the same.

In testimony whereof, we affix our signatures in presence of two witnesses.

ARTHUR WESLEY TEASLEY.
MILLARD VAN.
